(57) CLAIM

The ornamental design for a table, as shown and described.

DESCRIPTION

FIG. 1 is a front left perspective view of a first embodiment of a table showing my new design;
FIG. 2 is a top plan view thereof;

FIG. 3 is a front elevation view thereof, the side and rear views being identical;

FIG. 4 is a front left perspective view of a second embodiment of a table showing my new design;

FIG. 5 is a top plan view thereof;

FIG. 6 is a front elevation view thereof, the rear elevation view being a mirror image;

FIG. 7 is a left side elevation view thereof, the right side elevation view being a mirror image;

FIG. 8 is a front left perspective view of a third embodiment of a table showing my new design;

FIG. 9 is a top plan view thereof;

FIG. 10 is a front elevation view thereof the rear elevation view being a mirror image; and,

FIG. 11 is a left side elevation view thereof, the right side elevation view being a mirror image.

FIGS. 4-6 and 8-11 include break lines and those portions of the article between the break lines form no part of the claimed design.

1 Claim, 8 Drawing Sheets
